US0D1104286S

(12) United States Design Patent (10) Patent No.: US D1,104,286 S
(45) Date of Patent:  Dec. 2, 2025

(54) MASSAGE EQUIPMENT

(71) Applicant: TENGA Co., Ltd., Tokyo (JP)

(72) Inventor: Izumi Gemma, Tokyo (JP)

(73) Assignee: TENGA CO., LTD., Tokyo (JP)

() Term: 15 Years

(21) Appl. No.: 29/929,061

(22) Filed: Feb. 19, 2024

(30) Foreign Application Priority Data

Aug. 22, 2023 (JP) ..... 2023-016909 D

(51) LOC (15) Cl. 24-01

(52) U.S. Cl.

USPC D24/215

(58) Field of Classification Search

USPC D24/141, 200, 211, 212, 213, 214, 215

CPC A61H 19/44; A61H 19/32; A61H 19/34;

A61H 2201/0153; A61H 19/00; A61H

19/40; A61H 19/30; A61H 19/50

See application file for complete search history.
